COMBINED SNOW PLOW AND HANDLE THEREFOR OR SIMILAR ARTICLE

Jeffrey Douglas Golenski, Sacramento, Calif.
(405 Smith Neck Road, South Dartmouth, Mass. 02748)

Filed Sept. 1, 1967, Ser. No. 8,472

Term of patent 14 years

(Cl. D35—2)

FIG. I

FIG. II

FIG. III

FIG. I is a plan view of a combined snow plow and handle therefor or similar article showing my new design, the right end being planar and unornamented;

FIG. II is a side elevational view, the side opposite being similar in appearance; and

FIG. III is a perspective view.

I claim:

The ornamental design for a combined snow plow and handle therefor or similar article, as shown and described.
